(57) **CLAIM**

The ornamental design for a “hanging shelf”, as shown and described.

DESCRIPTION

FIG. 1 is a perspective view of a “hanging shelf” showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is the perspective view showing the practical usage thereof with the broken-line disclosure of a pair of toothbrushes being for illustrative purposes only and forming no part of the claimed design.
